Primary Examiner — John R Yeh*(74) Attorney, Agent, or Firm* — Fitch, Even, Tabin & Flannery LLP(57) **CLAIM**

We claim the ornamental design for a conduit strap part, as shown and described.

DESCRIPTION

FIG. 1 is a top front perspective view in accordance with our new design;

FIG. 2 is a top rear perspective view thereof;

FIG. 3 is a bottom rear perspective view thereof; and,

FIG. 4 is a bottom front perspective view thereof.

The portions shown in broken lines in the figures depict unclaimed environmental subject matter, are for illustrative purposes only, and form no part of the claimed design.
